UNITED STATES PATENT OFFICE

LENNA D. BALLEW, OF CHICAGO, ILLINOIS

DESIGN FOR A DOLL

Application filed April 5, 1933. Serial No. 47,703. Term of patent 7 years.

To all whom it may concern:

Be it known that I, LENNA D. BALLEW, a citizen of the United States, residing at Chicago, in the county of Cook and State of Illinois, have invented a new, original, and ornamental Design for a Doll, of which the following is a specification, reference being had to the accompanying drawing, forming a part thereof.

Fig. 1 is a front view of a doll showing my new design, and

Fig. 2 is a side view thereof upon a reduced scale.

I claim:

The ornamental design for a doll as shown.

LENNA D. BALLEW.
